UNITED STATES PATENT OFFICE

WILLIAM A. EDWARDS, OF CHICAGO, ILLINOIS, ASSIGNOR OF ONE-HALF TO WEBB JAY, OF CHICAGO, ILLINOIS, AND ONE-HALF TO STEWART-WARNER SPEEDOMETER CORPORATION, OF CHICAGO, ILLINOIS, A CORPORATION OF VIRGINIA.

CARBURETER.

1,317,967.

Specification of Letters Patent.

Patented Oct. 7, 1919.

Application filed November 19, 1915. Serial No. 62,284.

To all whom it may concern:

Be it known that I, WILLIAM A. EDWARDS, a subject of the King of Great Britain, residing at Chicago, in the county of Cook and State of Illinois, have invented certain new and useful Improvements in Carbureters, of which the following is a specification.

This invention pertains to carbureters for use in connection with gas engines, and has for its primary object the provision of a carbureter which will be extremely simple in construction and cheap to manufacture, which will consist of a minimum number of parts, which will be highly efficient and sensitive in operation, and which will not be apt to get out of order or require adjustment or repairs.

In carrying my invention into effect I employ a Venturi tube through which the air is supplied to the engine manifold. It is well known that when a stream of air is flowing through a Venturi tube there will be produced in the throat of the tube, or, in other words, a short distance beyond the point of minimum restriction of the tube, a vacuum, or at least a partial vacuum, which is disposed along the longitudinal axis of the tube. My present invention contemplates the introduction or delivery of the liquid fuel into this vacuum area or area of minimum pressure within the tube, so that the issuing fuel will be effectively volatilized, and also contemplates locating an air controlling valve within the throat of the Venturi tube by means of which the amount of air passing through the tube may be regulated.

By mounting the air valve and the fuel delivery nozzle or supply orifice in this particular location in the tube a direct suction will be exerted upon the fuel delivery orifice when the flow of air is cut down, which will be automatically superseded by a venturi action as the flow of air is issued. By reason of this construction I am able to dispense with the usual needle valve and to employ a fuel delivery orifice of constant size, the quantities of fuel issuing from this orifice being regulated by the position of the air controlling valve and the position of the fuel delivery orifice.

Another object is to so arrange and con-

nect the air controlling valve and the fuel delivery device that the supply of fuel will automatically vary in quantity proportionately to the variations in the quantity of air passing through the tube, with the result that a mixture of the required richness is delivered by the carbureter irrespective of variations in the engine speed.

Still another object of my invention is the provision of a novel accelerating well; i. e., a construction which will supply a supplemental charge of fuel to the vaporizing chamber when the engine is being started, to produce a very rich starting mixture.

Other objects and many attendant advantages of my invention should be appreciated as the same is better understood by reference to the following description when considered in connection with the accompanying drawings, on which—

Figure 1 is a longitudinal sectional view of a carbureter embodying my invention, taken on the line 1—1 of Fig. 2;

Fig. 2 is a transverse sectional view taken on the line 2—2 of Fig. 1; and

Fig. 3 is a detailed perspective view of the air controlling disk.

Fig. 4 is a detail section in the same plane as Fig. 1 showing the valve in the Venturi throat at closed position.

On the drawings reference character 5 designates generally the carbureter casing, which is shaped to provide a tube or cylinder 6, a downwardly extending spindle guide portion 7, and a laterally extending portion 8 forming the top of the float chamber, as will be later more fully described. The cylindrical portion 6 is provided at one end with a flange 9, by means of which the casing is attached to the manifold of an engine in the usual way, the opposite end of the cylinder being opened directly to the atmosphere or connected with suitable air heating means if preferred, the air supply being controlled at this end of the cylinder by the usual choker valve 11 adapted to be operated by the driver through any well known or preferred operating mechanism.

Within the cylinder 6 I have mounted a Venturi tube 12 which is intersected in its throat: that is, just to the right, viewing Fig. 1, of the point of minimum restriction by a spindle 13 which extends transversely

through the cylinder 6 and Venturi tube 12 and projects downwardly through the guide member 7 into the float chamber 14. The lower portion or body 15 of the float chamber 14, which may be of cast or sheet metal, is adapted to fit within the lower edge of the top portion 8 and is held in position preferably by a hollow nut 16 threaded through an opening in the bottom of the body 15 and into the tapped lower end of the spindle guide 7, as shown in Fig. 2. The spindle guide and the nut 16 are provided with drain openings 17 through which the float chamber may be drained by unscrewing the plug 18, as will be readily understood. A gasket 19 is preferably interposed between the float chamber sections 8 and 15 to insure a tight fit at their union.

Liquid fuel is supplied to the float chamber from any suitable source through a supply conduit or pipe 21 connected with the top of the chamber 14, the pipe being formed near its end to provide a valve seat 22. A frame comprising a circular portion 23, a rigid overlying arm 24 and an upwardly bent portion 25 at one end is pivoted at 26 within the float chamber and the arm 24 carries a valve plug 27 adapted to seat against the valve seat 22 to shut off the flow of fuel to the chamber. A float 28 is disposed in the float chamber and as the liquid in the chamber rises this float will be engaged by the circular portion 23 of the frame whereby the frame and the valve plug 27 will be lifted by the float until the fuel supply is shut off. It will be understood that as the fuel is withdrawn from the float chamber the float and the valve controlled thereby will move downwardly, permitting an inflow of fuel to the chamber.

The spindle 13, mounted as previously described, is provided in its lower portion with a longitudinally disposed bore 29 extending from the lower end thereof to a point within the lower wall of the Venturi tube 12. The lower end of the bore is closed by a plug 30 having a bleed opening 31 to permit a limited flow of fuel from the float chamber into the bore, or, as I term it, the accelerating well. A centrally disposed tube or duct 32 extending longitudinally through the well 29 projects at its lower end through the plug 31 into the float chamber and terminates at its upper end in the spindle 13 substantially on the longitudinal axis of the Venturi tube 12. At or adjacent to the upper end of the duct 32 the spindle is provided with a transverse opening 33 of substantially the same diameter as the duct and through which the bore communicates with the interior of the Venturi tube. Directly opposite to the opening 33 and in axial alignment therewith the spindle is provided with another opening 34 also communicating with the duct 32 but substantially twice the diam-

eter of the opening 33. It is through one or both of these openings, as the case may be, that fuel is delivered from the float chamber to the Venturi tube in a manner which will be later described. The openings, 33 and 34, together constitute a subsidiary air duct for permitting air to pass from the outer to the inner side of the valve at the closed position of the latter, and is herein-after referred to as the "subsidiary air duct." The opening, 34, having under certain conditions the function of relieving the suction of the fuel duct, 32, is hereafter referred to as the "suction relief" openings.

Above the upper end of the duct 32 the spindle is provided with a longitudinally extending slot 35 adapted to receive the web 36 of a valve disk 37 which is provided with a recess 38, the side walls of which are adapted to snugly fit the sides of the spindle when the disk is in operative position, as shown in Figs. 1 and 2. It should be observed at this point that the disk 37 is positioned on the spindle 13 to lie in a plane disposed at right angles to the axis of the aligned openings 33 and 34, and that these openings are substantially in the center of the disk and in the center of the Venturi tube, and that the diameter of the disk is only slightly less than the diameter of the Venturi tube along the axis of its intersection by the spindle 13 so that when said disk is disposed transversely of the tube it will nearly close the tube at this point. The spindle is oscillated for the purpose of controlling the air and fuel delivered from the carburetor by means of an arm 39 mounted upon the upper end of the spindle and fixed thereto by a pin 41 or other means. This arm is connected by suitable mechanism to the throttle lever of the machine so as to be operated in the usual manner.

The normal feed of the fuel from the float chamber to the Venturi tube is through the duct 32, but in order to supply a supplemental charge of fuel to furnish a rich starting mixture I have provided the following construction: A duct or tube 42 carried by the spindle 13 communicates at its upper end with the interior of the Venturi tube 115 through a laterally opening orifice 43 located beneath and in proximity to the orifice 34. The lower end of the tube 42 terminates a short distance above the bottom of the well 29. The upper end of the well 120 is in constant communication with the atmosphere through an elongated port 44 formed in the wall of the well and registering with a port 45 formed in the carburetor casing. The fuel in the well is therefore 125 subjected to atmospheric pressure at all times.

The operation of that embodiment of my invention herein shown for the purpose of illustrating the generic principles thereof 130

will now be described. When the engine is not running the level of the fuel in the well 29 and in the float chamber 14 will be substantially that indicated by the dotted line 46 in Fig. 2. Assuming that it is desired to start the engine, the choker 11 is set to nearly shut off the air supply and the spindle 13 is turned so as to dispose the disk 37 transversely across the throat of the Venturi tube, with the opening 34 toward the intake end of the tube and the opening 33 toward the delivery end. When the engine is turned over, either by hand or power, as the case may be, a direct suction is exerted upon the venturi, and the choker 11 being nearly closed a substantial vacuum will be produced in the venturi. Air will be drawn through the opening 34 and out the opening 33 across the top of the duct 32, which action will draw fuel up the duct 32 out through the opening 33 into the vaporizing chamber. The amount of fuel that will be delivered in this way is dependent, of course, upon the sizes of the openings 33 and 34 and the duct 32. The suction created in the venturi back of the disk 37 will also cause the fuel in the well 29 to discharge through the duct 42 and the orifice 43 into the intake end of the venturi, from whence it will be drawn with the air passing around the disk 37 through the venturi and into the manifold. This supplemental supply of fuel through the duct 42 from the well provides a starting charge, producing a very rich mixture during the acceleration period of the engine. As soon, however, as the level of the fuel in the well 29 falls below the end of the duct 42 air will be drawn through the duct and thereafter during the running of the engine only such quantities of fuel will be delivered by the duct 42 as enter the well 29 through the bleed opening 31. As the engine picks up the choker 11 may be opened and sufficient fuel will be supplied with the disk 37 closed to permit the engine to idle. When it is desired to speed up the engine the spindle 13 is turned by means of the lever 39, thus permitting more air to pass through the tube, and when the disk 37 has been turned parallel with the direction of the flow of air through the tube into the position in Figs. 1 and 2 the action of the carbureter will have changed from a direct suction to a true venturi action, and since the parts are so positioned and arranged that the openings 33 and 34 will be positioned in the zone of minimum pressure or, in other words, in the vacuum zone of the venturi it will be obvious that the fuel will be supplied as rapidly as is permitted by the size of the duct 32 and will be delivered into the vacuum zone of the venturi through both openings 33 and 34. As the engine is gradually throttled down by turning the spindle 13 the venturi action will be gradually dimin-

ished and the direct suction through the openings 34 and 33 will be gradually increased as the disk approaches its closed position. When the disk 37 is in closed position sufficient fuel will be supplied, as has been previously explained, through the opening 33 to permit the engine to idle, and as the disk is gradually opened the fuel supply will be increased proportionately to the increase in the amount of air passing through the tube until a maximum amount of fuel is delivered into the vacuum zone of the venturi when the disk 37 is wide open.

It is believed that the principles and the mode of operation of my invention will be understood from the foregoing without further description but it should be manifest that the details of construction illustrated and described are capable of considerable modification and variation without departing from the scope of the invention as defined in the following claims:

I claim:

1. In a carbureter, in combination with a Venturi tube inlet passage, a valve mounted within said Venturi passage near the most constricted portion thereof for closing the passage at that point, and a fuel inlet duct having its discharge mouth open at a point at the inner side of said valve at the closed position thereof.

2. In a carbureter, in combination with a Venturi tube air inlet passage, a throttle valve controlling the flow of air through the Venturi tube; a liquid fuel inlet tube having a suction relief passage extending from one side to the other of the valve at the closed position of the latter, and having its discharge opening positioned in the low pressure area of the Venturi tube.

3. In a carbureter, in combination with a Venturi tube air intake; a throttle valve mounted within said Venturi passage for turning therein to close the passage substantially at a trans-axial plane cutting the low pressure area thereof, and a fuel inlet tube having its discharge mouth at the inner side of the closed position of said valve.

4. In a carbureter, in combination with a Venturi tube air inlet passage, a pivoted throttle valve mounted for turning in the Venturi passage near the most constricted point thereof; a liquid fuel inlet tube whose terminal portion is rotatable with the throttle valve, and has its discharge mouth at the open position of said valve a short distance inward from the trans-axial plane of the apex of the Venturi tube and in the low pressure area of said tube.

5. In a carbureter in combination with a Venturi tube air inlet passage; a liquid fuel inlet tube, whose terminal portion is rotatable and which has two ports, one of which opens outward with respect to the Venturi tube at the closed position of the valve and

- which moves to a position for liquid discharge into the Venturi tube in the movement of the valve from closed to open position, and the other of which is in position for liquid discharge into said Venturi tube throughout all positions of the valve.
6. In a carbureter in combination with a Venturi tube air inlet passage, a throttle valve for controlling said passage; a fuel inlet having a discharge terminal rotatable with the opening and closing movement of the throttle valve, and having a suction relief opening positioned within the low pressure area of the Venturi tube, and which at the open position of the valve is turned in the direction to become fuel discharge mouth.
10. In a carbureter in combination with a Venturi tube air inlet passage, a spindle extending transversely through said tube, said spindle being provided at one end with a longitudinally extending fuel slot and at its other end with a longitudinally extending duct communicating with the interior of said tube through two aligned openings of different sizes, and a valve disk positioned in said slot in the spindles, said disk being provided with a recess to receive the spindle at the inner end of said slot, said disk being positioned within said tube at right angles to the aligned transverse openings of the spindle.
14. In a carbureter, the combination of a Venturi air intake tube, a spindle extending transversely through said tube, said spindle being provided at one end with a longitudinally extending fuel slot and at its other end with a longitudinally extending duct communicating with the interior of said tube through two aligned openings of different sizes, and a valve disk positioned in said slot in the spindles, said disk being provided with a recess to receive the spindle at the inner end of said slot, said disk being positioned within said tube at right angles to the aligned transverse openings of the spindle.
18. In a carbureter characterized as set out in claim 1, the fuel inlet being in the axial portion of the throttle valve, and having a suction relief opening at the side of the valve which is outward at the closed position of the latter.
22. In a carbureter characterized as set out in claim 1, the fuel inlet passage having in its terminal portion a suction relief opening and having said terminal portion formed in the throttle valve at the axial portion thereof, whereby the discharge and suction relief openings therefrom are openings in said valve.
26. In a carbureter characterized as set out in claim 1, the fuel inlet passage being provided with a suction relief opening larger than the discharge mouth of said passage.
30. In a carbureter characterized as set out in claim 9 foregoing, the discharge mouth and the suction relief opening being substantially co-axial at the center of the Venturi tube.
34. In a carbureter, the combination of a Venturi air intake tube, a spindle disposed transversely of said tube, constituting a fuel duct; a source of liquid fuel with which said duct communicates at one end, the other end being open in said Venturi tube, and an air-controlling device mounted on said spindle having a fuel discharge aperture which communicates with the last mentioned end of the fuel passage of the spindle and which is positioned within the low pressure area of the Venturi tube.
38. In a carbureter, the combination of a Venturi air intake tube, a spindle disposed transversely of said tube, having a fuel duct and a fuel delivery intake opening into the tube; an air controlling device mounted on said spindle having a liquid fuel discharge aperture communicating with the spindle duct and having the suction relief opening communicating with said discharge aperture and positioned at the low pressure area of the Venturi tube.
42. In a carbureter, the combination of a fuel chamber, a Venturi air intake tube located in proximity to said chamber, a spindle extending through said tube into the chamber, and provided with a longitudinally-disposed fuel duct communicating at one end with said chamber, a valve disk mounted on said spindle, said spindle being provided with a transverse opening establishing communication between said duct and said tube at one side of the disk, and also provided with another opening of smaller area establishing communication between said duct and the tube at the other side of the disk.
46. In a carbureter, the combination of a Venturi air intake tube, a spindle extending transversely through said tube, said spindle being provided at one end with a longitudinally extending fuel slot and at its other end with a longitudinally extending duct communicating with the interior of said tube through two aligned openings of different sizes, and a valve disk positioned in said slot in the spindles, said disk being provided with a recess to receive the spindle at the inner end of said slot, said disk being positioned within said tube at right angles to the aligned transverse openings of the spindle.
50. In a carbureter, the combination of a Venturi tube, a spindle extending transversely of said tube, a duct carried by said spindle for delivering fuel to the tube, an accelerating well carried by the spindle, and means for delivering the contents of said well to the tube when the engine is started.
54. In a carbureter, in combination with a Venturi air intake passage, a valve which controls the air inflow through such passage; a subsidiary air duct leading from a point which is at the outer side of the valve when the latter is at closed position, and which is at a point in the Venturi tube near the plane of greatest constriction thereof, to the side of the valve which is exposed to the engine suction at closed position of the valve, a liquid fuel supply duct constructed for discharging at said suction side of the valve in the Venturi passage proximate to the transverse plane at which the subsidiary air duct discharges.
58. In a construction such as set out in claim 16 foregoing, the subsidiary air duct being relatively restricted at its discharge end, and the liquid fuel supply duct being still more restricted at its discharge end proximate to the discharge end of the subsidiary air duct.
62. In a carbureter, in combination with a Venturi tube air inlet passage, a throttle valve mounted for turning within the throat of the Venturi tube, and a fuel inlet tube having its discharge mouth positioned at that side of the valve which at closed position is exposed to the engine suction.
66. In a structure such as set out in claim 180

18 foregoing, a subsidiary air inlet duct which has its intake end at the outer side of the closed position of the valve and its discharge end at the inner side of said closed 5 position, and proximate to the discharge of said fuel inlet tube, whereby at the closed

position of the valve, the subsidiary air supply impinges upon and tends to mix with the fuel delivered through said fuel inlet tube.

WILLIAM A. EDWARDS.
